UNITED STATES PATENT OFFICE.

LOGAN WILLARD MULFORD, OF NARBERTH, PENNSYLVANIA, ASSIGNOR OF ONE-HALF
TO FREDERICK J. GEIGER, OF PHILADELPHIA, PENNSYLVANIA.

METHOD OF CONSTRUCTING A CONCRETE SKYLIGHT, VAULT-LIGHT, AND FLOOR-LIGHT.

1,072,147.

Specification of Letters Patent.

Patented Sept. 2, 1913.

Application filed February 23, 1912. Serial No. 679,464.

To all whom it may concern:

Be it known that I, LOGAN WILLARD MULFORD, a citizen of the United States, residing at Narberth, in the county of Montgomery, State of Pennsylvania, have invented a new and useful Method of Constructing Concrete Skylights, Vault-Lights, and Floor-Lights, of which the following is a specification.

10 In devices of this character, as heretofore manufactured, it has been impracticable, owing to the cost of transportation from the factory to the place of usage, and also from the great liability to breakage in transit, and further the impossibility of making a first class installation at the building, to substantially complete the construction before shipping and where long hauls are necessary the cost of transportation has 20 rendered such methods commercially impracticable.

The object of my present invention is to devise a novel method of constructing a sky light, vault light and floor light where 25 by the construction may be partially or substantially completed at the factory and then shipped to its destination, at which place it may be readily placed in position by unskilled labor, the parts being constructed in 30 such a manner that the elements thereof are not in danger of being moved out of alignment with consequent detriment to the finished construction, and my novel method also provides a construction in which the 35 top finish and the watertight finishing work can be done at the building, thus accomplishing the same purpose as when the entire work of construction is done at the building, and at the same time greatly reducing the cost of construction.

40 My invention in its broad and generic scope consists of a novel method wherein a concrete slab having tile or lens receiving openings is built up, after which such slab 45 is shipped to its destination and located in position, then the openings are covered by the lenses or tiles, and then the construction is completed by pouring on the concrete in such a manner as to embed the tiles and seal 50 them in proper position.

In a co-pending application, filed on the 3rd day of June, 1911, Serial No. 631,084, I have described and broadly claimed a 55 novel sky light, vault light and floor light construction, and my present application

relates to a novel method of constructing a sky light, vault light and floor light construction, such as is disclosed therein.

For the purpose of illustrating different ways of carrying out my novel method, I 60 have shown in the accompanying drawings preferred embodiments thereof which have been found in practice to give satisfactory and advantageous results, although it is to be understood that the various instrumentalities of which my invention consists can be variously arranged and organized and that my invention is not limited to the precise arrangement and organization of these instrumentalities as herein shown and described. 70

Figure 1 represents a perspective view of a portion of a sky light, vault light and floor light construction embodied in my invention. Fig. 2 represents a sectional elevation of Fig. 1. Fig. 3 represents a perspective view showing the construction as manufactured at the factory and ready for shipment. Fig. 4 represents a perspective view of another embodiment of my invention showing the same as ready for shipment. Fig. 5 represents a sectional elevation of Fig. 4 but showing in addition a lens in place and the binding material in co-operative relation with respect thereto. 80 Fig. 6 represents a plan view of the finished construction partly broken away to show more clearly one type of metal reinforcement. Fig. 7 represents a perspective view of another embodiment of my invention. Fig. 8 represents a sectional elevation of Fig. 7 but showing in addition a tile in position and the binding material in co-operative relation with respect thereto. Fig. 9 represents a plan view of Fig. 8. Fig. 10 represents a plan view showing the position the parts assume during the first step of the operation, before the first layer of concrete is in position. Fig. 11 represents a section on line $x-x$, Fig. 10. Fig. 12 represents a sectional view showing the first set of reinforcements and the bonding elements embedded in the concrete, and the lens forming castings removed. Fig. 13 represents a sectional view of the construction, showing the first slab as complete and the upper set of reinforcements secured to the bonding elements. 100 105

Similar numerals of reference indicate corresponding parts in the figures. 110

Referring to the drawings: My invention in its broad and generic scope and in its simplest form consists of a concrete slab, having tile receiving openings, which is adapted to be located in position and after the tiles have been placed in their proper positions above the openings, a second layer of concrete is formed thereon which embeds the tiles and finishes the construction, and in order that my method may be more clearly understood I have shown herein certain embodiments thereof which may be advantageously employed in practice.

In all of the embodiments of my invention herein illustrated, I have shown a construction which is preferably completed at the factory to such an extent that it is adapted to receive the lenses or tiles, and provided with bonding elements adapted to receive rods or bars of any desired contour so that after the partly completed construction is received at its destination, the rods or bars may be assembled with respect to the bonding elements, the lenses placed in position and embedded in the binding material which unites with the bonding elements, so that the binding material which is pre-formed, will be united in a reliable and stable manner with the binding material which embeds the lenses and secures them in position.

Referring first to the embodiment seen in Figs. 1 to 3 inclusive, 1, as indicated in Fig. 3, designates the construction as completed ready for shipment, and wherein a foundation or layer of binding material 2 of any desired nature is employed, which in the present instance, forms a layer of substantially uniform thickness and is provided with openings 3 therethrough adapted to receive the lenses or tiles 4 which may be of any desired character and which, in the present instance, are illustrated as provided with the laterally extending flanges 5 and 6 between which is located a laterally extending groove 7 which extends into the body portion of the tile in order to provide a space adapted to be filled with binding material.

8 designates rods or bars which may have any desired contour and are preferably arranged parallel with respect to each other, it being noted that rods or bars 9 extending at right angles to the bars 8 are employed in order to reinforce the concrete. These rods or bars 8 or 9 may be round or deformed, that is, they may have either a round contour or any other desired contour may be given thereto and still be within the scope of my invention. The rods or bars 8 and 9 respectively are arranged in any desired manner, in the present instance in different horizontal planes, the rods 9, in the present instance, being located in the layer 2, while the rod 8 is located in a plane thereabove,

and these members 8 and 9 are embedded in the same binding material as that which forms the layer 2 in order to form dovetail projections 10 which intersect each other, as will be best apparent from Fig. 3.

It will of course be understood that in the process of manufacture the members 8 and 9 are supported in a suitable form or mold so that when the binding material is placed therein a construction such as is seen in Fig. 3 will be formed, in which the layer 2 and dovetail members 10 are simultaneously produced.

After the construction has been completed to the extent indicated in Fig. 3, the same is ready for shipment to the desired destination. After being located in its proper position the lenses or tiles 4 are placed in position above the openings 3 so that the rib 6 will surround the walls of such opening, after which the binding material 11 is placed in position so as to embed the tiles and interlock with the ribs 5 and 6 and the groove 7 therebetween and also interlock with the dovetail members 10 so that when the parts are in assembled position the binding material 11 will be united in a positive manner with respect to the binding material 2 and the members 10.

In the embodiment seen in Figs. 4 and 5 inclusive, I have shown the metal reinforcements as consisting of any desired number of layers of apertured or expanded metal 12 through which passes bonding elements 13, which, in the present instance, are shown as having their ends secured together and embedded in the concrete although, as will be apparent, the ends of the bonding elements 13 may extend above the layer of preformed concrete. In this embodiment the bonding elements 13 extend throughout the construction thereby adapting the same to receive the rods 14 and 15 which in this embodiment, I have illustrated as being of rectangular contour. The construction, comprising the concrete base 16 having the tile receiving apertures 17 therein and the bonding elements 13, may be shipped from the factory either with or without the rods 14 and 15 in assembled relation with respect thereto. The tile 4 is constructed in a similar manner to that already described with reference to Figs. 1 to 3 inclusive and is secured in position by means of the binding material 11 in a similar manner, it being seen that the binding material embeds the bonding elements 13 and the rods 14 and 15 so that a bond or tie is formed between the old concrete or binding material and the new concrete or binding material.

In the embodiment seen in Figs. 7 to 9 inclusive, I have shown a construction wherein a different type of bonding elements is employed and in this embodiment the bonding elements consist of strips 18

preferably metallic and provided with apertures 19 and 20, the apertures 20 being adapted to receive the rods 21 which in this instance are embedded in the lower concrete 5 layer 16 while the upper ends of the members 18 are adapted to receive rods 22, it being understood that similar binding elements 18 are employed through which are adapted to pass the rods 23 which are embedded in the preformed concrete, and rods 24 which latter are adapted to be embedded in the concrete which is used to embed the tiles and form a bond with the bonding elements 18 and the rods 22 and 24. It will 10 be readily apparent from Fig. 8 that the binding material interlocks with the tile in a similar manner to that already described with reference to other figures of the drawings.

15 Referring now to Figs. 10 to 13 inclusive, I have illustrated therein one manner of carrying out the novel steps of my method it being seen that I first take a form or support 25 of any desired dimensions and provided 20 with apertures 26 therethrough which are spaced apart. The apertured support 25 thus formed is supported in any desired manner. Any desired means may be employed to confine the concrete to form the 25 sides of the slab to be formed but, in the present instance, I have shown this as being accomplished by placing strips 29 of any desired material on the top of the support 25 in order to form a mold for the concrete 30 mixture. The strips 29 may be secured in position by any desired means such as for example the clamping devices 30. Castings 31 having any desired contour and designed to form the lens receiving openings are then 35 placed in position to cover the apertures 26. The castings 31 are shown as provided with an aperture 32 therethrough and having its outer periphery tapering as is indicated at 33 while the lower portion thereof is angularly recessed as at 34 thereby adapting the 40 same to seat on the support 25. Reinforcing members such as the rods 35 are then placed in position between the castings or molds 31 such reinforcing members being spaced 45 from the support 25 by spacing devices 36 of any desired construction. Reinforcing members 37 are then located between the molds 31 so as to extend at an angle to and traverse the reinforcing members 35 to which latter 50 they are secured by bonding elements 38 of any desired construction but which for convenience of illustration I have shown as comprising a wire or cable which is twisted around the reinforcing members 35 and 37 55 at their points of intersection and the free ends of the wire extend upwardly above the top of the mold 31 as will be understood by reference to Fig. 11 and as indicated at 39 in said figure. The parts 60 now appear as indicated in Fig. 10 ex- 65

cept that in said figure certain of the molds 31 have been omitted for clearness of illustration. The next step is to pour the concrete or other binding material employed on to the support 25 in order to embed the 70 reinforcing members 35 and 37 and the lower portion of the bonding elements 38 and then allowing the concrete or binding material to set to form a reinforced concrete slab 40 as will be clearly understood 75 by reference to Fig. 12. After the concrete is set the clamps 30 and the strips 29 are removed and the concrete slab 40 is removed from the support 25 and the molds 31 are taken away thereby leaving lens receiving 80 apertures 41 in the concrete, as is clearly indicated in Fig. 13. The reinforced concrete slab 40 thus formed may be shipped to its destination or if desired reinforcing members 42 may be secured to the ends 39 of the 85 bonding elements 38 and then reinforcing elements 43 extending at an angle to the elements 42 may be secured to the bonding elements 38 and the construction thus far completed shipped to its place of installation 90 at which place the lenses will be placed in position and the second layer of concrete be formed to finish the construction. It will thus be seen that a reinforced concrete slab 95 is formed having reinforcements of any desired nature and with tile receiving openings and bonding elements while the tiles are placed in position and embedded in another layer of concrete.

In many cases arising in practice it is 100 advantageous to provide a concrete slab or a reinforced concrete slab having the tile receiving openings therein with bonding elements of any desired nature, so that after the tiles are placed in position and the second layer of concrete is formed a positive bond or tie will be produced between the preformed concrete construction and the concrete which embeds the tiles 105

In many cases arising in practice it is 110 advantageous to reinforce not only the first layer of concrete but also the second layer of concrete and in such case I preferably interlock with or secure to the bonding elements in any desired manner the reinforcements of the second layer of concrete. 115

It will be apparent to those skilled in the art that when concrete or similar binding material is applied to a preformed concrete slab, as shown in the various embodiments 120 of my invention, that the union of the preformed and subsequent formed slabs, is effected on a neutral axis, the tension stress being exerted on the preformed or lower slab and the compression stress on the upper 125 slab, the ingredients of the slabs uniting as a homogeneous mass after the operation is completed, so that an intimate union between the upper and lower layers of concrete is effected, without the use of bonding ele- 130

ments although in practice I prefer to employ such bonding devices.

In so far as I am aware, I am the first in the art to form a concrete slab having tile receiving openings so that the same may be shipped from the factory and wherein the construction is completed by locating such concrete slab in its proper place, placing the tiles thereon and then pouring on concrete to embed the tiles and secure them in position and it is to be understood that my claims to such features are to be interpreted with corresponding scope.

It will now be evident to those skilled in this art that I have devised a construction which may be partially or substantially completed at the factory so that the openings for the tile will be properly aligned and a reinforced concrete slab produced which may be placed in position by unskilled labor. The tiles may then be placed in position and it is simply necessary to pour in the concrete which unites with the bonding elements, as herein described, so that a firm bond or tie between the old concrete and the new concrete or other binding material is produced.

In devices of this character, as heretofore constructed, it has been necessary to send a skilled workman from the factory to assemble the devices, but when devices are employed constructed in accordance with my novel invention, the same may be readily assembled by unskilled labor with a consequent economy in the cost of construction.

It will now be apparent that I have devised a novel and useful method of constructing concrete skylight, vault light and floor light which embodies the features of advantage enumerated as desirable in the statement of the invention and the above description, and while I have, in the present instance, shown and described a preferred embodiment thereof which has been found in practice to give satisfactory and reliable results, it is to be understood that the same is susceptible of modification in various particulars without departing from the spirit or scope of the invention or sacrificing any of its advantages.

Having thus described my invention, what I claim as new and desire to secure by Letters Patent, is:

1. The method of forming a concrete sky light, vault light or floor light, which consists in taking an apertured support, placing molds over the apertures, spacing reinforcements from the support, placing on the support molding elements to form the sides of the slab, embedding the reinforcements in concrete, allowing the concrete to set, then removing the reinforced concrete slab from the support, the molds and the molding elements, placing the slab over a vault, floor, or sky light opening, placing lenses over the

openings in the slab to project above it, and then embedding said lenses in concrete.

2. The method of forming a concrete sky light, vault light or floor light, which consists in taking an apertured support, placing molds over the apertures, spacing reinforcements from the support, placing on the support molding elements to form the sides of the slab, uniting with the reinforcements bonding elements, embedding the reinforcements and a portion of the bonding elements in concrete, allowing the concrete to set, then removing the reinforced slab with lens receiving openings from the support, the molds, and molding elements, placing said slab over a vault, floor or sky light opening, placing lenses over the openings in the slab to project above it, embedding the exposed bonding elements, and surrounding the lenses flush to the top thereof with concrete, and then allowing the second layer of concrete to set.

3. The method of forming a concrete sky light, vault light or floor light, which consists in first positioning reinforcing devices, next securing to the reinforcing devices bonding elements, embedding the reinforcing devices and a portion of the bonding elements in concrete, then allowing the concrete to set to form a reinforced concrete slab with lens receiving openings and exposed bonding elements, placing said slab over a vault, floor or sky light opening, placing lenses over the opening in the slab to project above it, embedding the exposed bonding elements of the second set of reinforcing devices, and surrounding the lenses flush to the tops thereof with concrete, and then allowing the second layer of concrete to set.

4. The method of forming a concrete sky light, vault light or floor light, which consists in first positioning reinforcing devices, securing to the reinforcing devices bonding elements, embedding the reinforcing devices and a portion of the bonding elements in concrete to form a reinforced concrete slab with lens receiving openings and exposed bonding elements, allowing the concrete to set, then securing to the exposed portion of the bonding elements a second set of reinforcing devices, placing said slab over the vault, floor or sky light opening, placing lenses over the openings in the slab to project above it, embedding said lenses flush to the tops thereof and the reinforcements in concrete, and then allowing the concrete to set.

5. The method of forming a concrete sky light, vault light or floor light, which consists in first positioning reinforcing devices, embedding them in concrete to form a reinforced concrete slab with lens receiving openings, placing lenses over said openings to project above the slab, and then embed-

ding said lenses in concrete flush to the top thereof.

6. The method of forming a concrete sky light, vault light or floor light, which consists in positioning reinforcing devices, uniting with the reinforcing devices bonding elements, embedding the reinforcing devices and a portion of the bonding elements in concrete to form a reinforced concrete slab 10 with lens receiving openings and exposed bonding elements, placing lenses over the openings to project above the slab, embedding the exposed bonding elements and surrounding the lenses flush to the top thereof with concrete, and then allowing the second 15 layer of concrete to set.

7. The method of forming a concrete sky light, vault light or floor light, which consists in positioning reinforcing devices, uniting with the reinforcing devices bonding elements, embedding the reinforcing devices 20 and a portion of the bonding elements in

concrete to form a reinforced concrete slab with lens receiving openings and exposed bonding elements, securing a second set of 25 reinforcing devices to the bonding elements, placing lenses over the openings to project above the slab, embedding the exposed bonding elements and the second set of reinforcing devices, and surrounding the lenses flush 30 to the tops thereof with concrete, and then allowing the second layer of concrete to set.

8. The method of forming a concrete sky light, vault light or floor light, which consists in forming a reinforced concrete slab 35 with lens receiving openings and exposed bonding elements, placing lenses over the openings, embedding said lenses flush to the tops thereof and the reinforcements in concrete, and then allowing the concrete to set. 40
